(57) **CLAIM**

The ornamental design for a limited slip differential, as shown and described.

DESCRIPTION

FIG. 1 is a perspective view of a limited slip differential showing our new design;

FIG. 2 is a first side view thereof;

FIG. 3 is a second side view thereof;

FIG. 4 is a top view thereof;

FIG. 5 is a bottom view thereof;

FIG. 6 is a front view thereof; and,

FIG. 7 is a rear view thereof.

The broken line showing in the figures is included for the purpose of illustrating portions of the limited slip differential and forms no part of the claimed design.
